CLAIM

The ornamental design for a display screen or a portion thereof with a graphical user interface, as shown and described herein.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with a graphical user interface of our new design. The outer perimeter broken lines in the drawing represent a display screen or portion thereof and form no part of the claimed design.
